UNITED STATES PATENT OFFICE.

HAROLD J. NAGLE, OF ROCHESTER, NEW YORK, ASSIGNOR, BY MESNE ASSIGNMENTS,
TO CEDAROID CO. INC., OF ROCHESTER, NEW YORK, A CORPORATION.

BOX FOR CIGARS.

1,319,788.

Specification of Letters Patent.

Patented Oct. 28, 1919.

Application filed March 20, 1915. Serial No. 15,737.

To all whom it may concern:

Be it known that I, HAROLD J. NAGLE, of Rochester, in the county of Monroe and State of New York, have invented a new 5 and useful Box for Cigars, fully set forth in the following specification and shown in the accompanying drawings.

The present invention relates to boxes for cigars and it has for an object to provide a 10 construction which is made from wood pulp and will not communicate deleterious odors to the cigars and, at the same time, will permit the moisture from the cigars to escape without causing them to become too dry and 15 without admitting too much moisture or any odors from the surrounding atmosphere.

To these and other ends, the invention consists in certain parts and combinations of parts all of which will be hereinafter 20 described, the novel features being pointed out in the appended claim.

In the drawings:

Figure 1 is a front view of a box constructed in accordance with the present invention;

Fig. 2 is a front view of the box before the border strips are placed thereon;

Fig. 3 is an enlarged section on the line *a—a*, Fig. 1;

Fig. 4 is an enlarged section on the line *b—b*, Fig. 1; and

Fig. 5 is an enlarged section on the line *c—c*, Fig. 1.

In the present embodiment of the invention, the side walls and the bottom wall of 35 the box are made from a single blank of solid woodpulp board which is chemically pure that is, it is non-filled and has no paper or rag stock. To simulate a cedar box, 40 this board is coated on both sides with a stain which has an odor of cedar with all other odors eliminated or substantially so. The board is preferably about one-quarter of an inch thick and the side walls 1 are in 45 one piece with the bottom wall 2, the blank being scored and the side walls being turned at right angles to the bottom wall and providing channels or grooves 3 entirely about the bottom wall at the base of the side walls.

50 The side walls 1 may be provided with horizontal grooves or channels 4 preferably in proximity to their upper and lower edges on the front face thereof, and also with vertical channels 5 near opposite ends intersecting the channels 4 and extending from

the upper to the lower edges of said wall so as to connect also with the base channel 3. The bottom wall 2 is also provided with channels 6 parallel with the longitudinal edges of said wall and also parallel with 60 the transverse edges of the wall, said channels intersecting each other in proximity to the corners of the boxes and also intersecting the base channel 3. The channels 4, 5 and 6 are provided at intervals with openings 7 which extend through the wall of the box, and openings 16 provide communication between the channel 3 and the interior of the box.

The corners of the box are held together 70 by staples 8 which not only pass into the side walls but pass through a reinforcing strip 9 of heavy manila stock which is bent about the corners and adhesively secured thereto. Border strips 10 are secured over 75 all corners of the box and also over the upper edges of the side walls. These strips bridge the channels 4, 5 and 6 so as to close the same to the external atmosphere thus providing, in the box walls, a number of 80 communicating channels which open to the interior of the box. By this arrangement, the moisture in the cigars is permitted to escape very slowly through the openings 7 into the channels 4, 5 and 6 and is absorbed 85 by the thin paper covering or border strips 10 which are dried by the external atmosphere. At the same time, these strips prevent the entrance of any external odors and, even though they absorb moisture from the 90 external atmosphere, such moisture will not penetrate the box to any great extent as it will be dried before passing through the small openings.

It is desirable that the two end side walls 95 1 shall project slightly above the front and rear side walls so that their upper edges shall be flush with the upper face of the cover 11 which is hinged at 12 in the usual manner to the rear side wall and rests on 100 the upper edge of the front side wall as is common in cigar boxes. A tack which is usually employed for securing a cigar box cover has been found undesirable in this box as it tends to separate the laminations 105 of the front walls and for this reason I have designed a novel means of securing the cover in closed position without penetrating the paper board in the direction of its laminations. This means embodies a 110

tongue 13 formed of flexible metal stock and secured on the inner face of the front wall preferably by an eyelet 14 which passes through a perforation in the front wall coincident with the channel 4 so that it also serves to connect said channel with the interior of the box. As the outer end of the eyelet lies in the channel, it is covered by the border and in this way is not visible 10 on the exterior of the box. The cover 11 is provided with a slit 15 in proximity to its edge and the tongue is passed through this slit and bent forwardly and downwardly as shown in Fig. 5 thus securing 15 the cover in closed position.

It is apparent that there has been provided an inexpensive box made from wood stock and not communicating a deleterious odor to the cigars while at the same time permitting the moisture to escape slowly 20 without admitting an undue amount of moisture or any external odors.

What I claim as my invention and desire to secure by Letters Patent, is:

A tobacco receptacle having a wall formed 25 with an exterior channel opening at intervals to the interior of the box, and a paper covering on the exterior of the box closing said channel.

HAROLD J. NAGLE.
